(57) **CLAIM**

The ornamental design for "profiled rail for advertising/display units," as shown and described.

DESCRIPTION

FIG. 1 is a right, top, rear perspective view of a profiled rail for advertising/display units in accordance with a first embodiment of my new design;

FIG. 2 is a right, bottom, front perspective view thereof;
 FIG. 3 is a right side elevation view thereof; the left side view being a mirror image thereof;

FIG. 4 is a right, top, rear perspective view of a profiled rail for advertising/display units in accordance with a second embodiment of my new design;

FIG. 5 is a right, bottom, front perspective view thereof;
 FIG. 6 is a right side elevation view thereof; the left side view being a mirror image thereof;

FIG. 7 is a right, top, rear perspective view of a profiled rail for advertising/display units in accordance with a third embodiment of my new design;

FIG. 8 is a right, bottom, front perspective view thereof; and,
 FIG. 9 is a right side elevation view thereof; the left side view being a mirror image thereof.

1 Claim, 9 Drawing Sheets
